CLAIM

The ornamental design for a visible step neutral bar, as shown and described.

DESCRIPTION

FIG. 1 is a perspective view of the visible step neutral bar of the present invention;

FIG. 2 an end view;

FIG. 3 is a side view;

FIG. 4 is a top view; and,

FIG. 5 is a bottom view.

The visible step neutral bar is shown broken away in FIG. 1, 3, 4, and 5 of the drawing to indicate indeterminant length, it being understood that it has a uniform shape and appearance through out its length.
